SCARIFIER

Ira Sublett, St. Louis, Mo., assignor to Fairmont Railway Motors, Inc., Fairmont, Minn., a corporation of Minnesota

Application November 3, 1939, Serial No. 302,677

4 Claims. (Cl. 262—8)

My invention relates to improvements in scarifiers of the nature disclosed in Letters Patent of the United States, No. 1,951,166, issued March 13, 1934, to H. W. Protzeller, and pertains to that type of scarifying element including a scarifier tooth and a hanger bar therefor adapted to be carried by a vehicle or other traveler.

In scarifying equipment of the character disclosed in said Patent No. 1,951,166 for maintaining rock ballast of railway tracks and in similar equipment for other specific purposes, the vehicle or other traveler employed is supplied with hanger bars upon which scarifier teeth are detachably mounted so that they may be readily replaced and also readily interchanged between the various hanger bars. Replacement of teeth is desired in order that new ones may be substituted for those which have become entirely worn out. The interchanging of teeth from one hanger bar to another is desired, not only to provide for uniformity in the wear thereof under conditions wherein the leading portions of the teeth are caused to wear off at one corner or the other, as in scarifying ballast at opposite sides of a railway track, but also to provide for increased effectiveness of such corner-worn teeth in their new positions and the concurrent self-sharpening of the same preparatory to the return thereof to their original positions.

It is an object of my invention to provide a relatively simple and durable scarifying element of the present nature consisting of parts so constructed and arranged that the initial costs and costs of maintenance are comparatively low.

A further object of the present invention is to provide a scarifier element including a relatively inexpensive holder which is readily detachably mounted on a hanger bar and upon which the tooth of the element, in turn, is readily detachably mounted.

Another object of the invention resides in providing for simplicity and security of attachment of the scarifier tooth to the holder and of the holder to the hanger bar, a further object being to provide a tooth and holder of such design that the tooth may be worn substantially entirely away, and the hanger appreciably worn before being rendered useless in the assembly.

An additional object of the invention is to provide a holder of the present nature that is readily endwise reversible on the hanger bar, whereby a holder structure of limited size and weight and of relatively inexpensive material, will afford alternate supports for the tooth, the one being

available for use upon the impairment of the other.

A further object of the invention is to supply a holder of composite construction consisting of a pair of holder members, each of which is adapted interlockingly to engage the unitarily formed tooth, the composite construction of the holder necessitating the replacement only of the particular holder member required to be discarded because of wear sufficient to impair the attachment of tooth to holder.

A feature of the invention, directed to the promotion of economy in production costs, resides in providing reversible holder members of identical construction having opposed tip portions, either of which may be presented in leading position to support the tooth.

Other objects of the invention reside in the novel combination and arrangement of parts and in the details of construction hereinafter illustrated and/or described.

In the drawings, Fig. 1 is a side elevational view of a scarifier element embodying my invention; Fig. 2 is a sectional view taken as on the line 2—2 of Fig. 1; Fig. 3 is a perspective view in detail illustrating the scarifier tooth as seen from the rear and one side thereof; Fig. 4 is a perspective view of the assembled parts making up my improved scarifier element, a portion of the hanger bar being broken away; Figs. 5 to 8 inclusive are perspective views illustrating the several parts of the assembly shown in Fig. 4; Fig. 5 showing the lower end of the hanger bar, Fig. 6 and Fig. 7 showing the two identical plate-like members of the composite tooth holder, and Fig. 8 showing the scarifier tooth; Fig. 9 is an elevational view of an incomplete assembly which includes the hanger bar, the tooth, and one of the holder members, the second holder member 40 that normally would be last applied to the assembly being omitted.

Reference being had to the accompanying drawings, wherein similar parts are designated by similar reference characters throughout the several views, it will be seen that my improved scarifier element includes a hanger bar A, a composite tooth holder B, and a unitary tooth C.

The hanger bar A has a series of bolt holes 10 in the upper portion thereof for the reception of bolts, employed in the usual manner, for clamping said hanger bar, in upright position, to a wing frame or other frame member of a vehicle or traveler. The lower end portion of the hanger bar A is formed with two openings 11, 12 of circular conformation disposed in line transversely

of the hanger bar, each of said openings being equi-distant from a medial line longitudinally of the hanger bar. Also formed in said hanger bar A and extending transversely thereof beneath said openings 11, 12 is a third opening in the form of a slot 13, said slot being centered on said medial line of said hanger bar. These openings 11, 12 and 13 provide sockets at opposite sides of the hanger bar for the reception of bosses on the tooth holder B, as will soon appear.

The tooth holder B is an elongated composite structure consisting of a pair of identical members b. Each holder member comprises a body-plate 14 generally in the form of an isosceles triangle, the angle at the apex being decidedly obtuse. Each member b thus includes a medial portion and two opposed tip portions. All of the corners of each member are somewhat rounded. In rounding the bottom corners, the edges of the body-plate 14 at the sides thereof, near the base, are arcuately curved downwardly, such curved reaches of said edges together with the adjacent planar reaches thereof forming seats 15 adapted to be engaged by the tooth C. Reinforcing each holder member b and adding width to the edge of its body-plate 14, is a continuous marginal flange 16 which is formed integrally with said body-plate at the outer face thereof. Each tip portion of each holder member b is formed with a bolt-receiving bore 17, the same being eccentrically disposed with reference to the center of curvature of the arcuately curved reach of the adjacent seat 15. Each tip portion of each holder member b is further formed with an integral stop lug 18 located at the base of the body-plate 14, forwardly of the corresponding bolt-receiving bore 17, said lug projecting from the inner face of the holder member. The medial portion of each holder member b has four integrally formed bosses 19, 20, 21 and 22 thereon. These bosses project from the inner face of the member and each boss has an axial bolt-receiving bore therein which extends through body-plate 14 of said member. The bosses 19, 20 are centered on a right line passing through the apex of the holder member, boss 19 being near the apex of said member and boss 20 being near the base thereof. The bosses 21, 22 are located at opposite sides of said right line, near the edge of the holder member at the sides thereof.

The tooth C is constructed of material highly resistant to wear and much more so than the comparatively less costly material from which the holder members b are constructed. Said tooth C consists of an elongated body 23 formed with a rib 24 extending along the top thereof, said body and rib being shaped to provide a bit or point 25 at the leading tip of the tooth. Depending from the trailing portion of the tooth body 23 is an abutment 26, and formed integrally with said abutment and also with said tooth body is a tongue 27 having a bolt-receiving opening 28 therein. At either side of the tongue 27, the lower face portion of the tooth body 23 and the corresponding trailing face portion of the abutment 26 constitute a bearing 29 for the tooth, said lower face portions of the tooth body being in a plane to conform with the planar reaches of the seats 15 on the holder members b, while said trailing face portions of said abutment are curved to conform with the arcuately curved reaches of said seats 15.

The several parts of my improved scarifier

element are conveniently assembled. The hanger bar A being clamped in place, either edge foremost, to a mobile supporting structure, one of the holder members b, as shown in Fig. 9, is applied to one side of the hanger bar A with the leading tip portion of said member in a depressed position relative to the position occupied by the trailing tip portion. Said holder member b is thus applied to the hanger bar A by socketing the bosses 19, 20 and 21 in the openings 11, 12 and 13, respectively, of said hanger bar. Bolts 30, 31, 32 and 33 are then inserted into and through the bores of the bosses 19, 20, 21 and 22, respectively, and a fifth bolt 34 is inserted into the bore 17 in the then leading tip portion of said holder member b. The tooth C is then applied to the seat 15 of said tip portion with the bearing 29 at the one side of the tongue 27 bearing upon said seat and with the lower edge of said tongue resting upon the adjacent stop lug 18. Said fifth bolt 34 is then pushed through the bore 17 in the holder member b and the registering opening 28 in said tongue 27. Thereupon, the second holder member b is applied to the hanger bar A at the side opposite to that occupied by the first holder member b, such application being attended with the reception by said second holder member of the bolts 30, 31, 32 and 33 in the bores of the bosses 19, 20, 22 and 21, respectively, and of the bolt 34 in the bore 17 at the leading tip portion of said second member b. Also attending the application of said second holder member b to the hanger bar A is the socketing of the bosses 19, 20, and 22 of said member in the openings 11, 13 and 12, respectively, of the hanger bar A, as said second holder member is moved into place along said bolts. With said first and second holder members b thus positioned in registry with each other against opposite sides of the hanger bar A, the lower edge of the tongue 27 of the tooth C rests against the stop lug 18 issuing from the leading tip portion of said second member b as well as against the stop lug 18 issuing from the mating tip portion of the first holder member, and the second bearing 29 of said tooth C bears against the seat 15 on the leading tip portion of said second holder member in the same manner in which said first bearing 29 of said tooth bears against the seat 15 on said mating portion of said first holder member b. The entire assembly is clamped together by applying washers 35 and nuts 36 to said bolts and turning said nuts against the outer face of the second holder member b to bring the heads of said bolts tightly against the outer face of said first holder member b. In further clamping the holder members together, a sixth bolt 37, received in the bores 17 at the trailing tip portions of said members, is preferably used. The bosses 19, 20, 21 and 22 and the stop lugs 18 on each holder member b extend from the inner face of such member a distance slightly less than one-half the thickness of the hanger bar A and the equally thick tongue 27 of the tooth C. Thus the ends of said bosses and the ends of the leading stop lugs 18 on the two holder members are kept from contacting each other and are thereby precluded from interfering with the rigid clamping of said members against the hanger bar A and said tongue 27 of said tooth C. The rearmost stop lugs 18 on the assembled holder members b will, however, come into contact with each other should the sixth clamping bolt 37, in the trailing tip portions of said members, tend to spring

said portions toward each other. Thus, it will be seen that those of the lugs 18 disposed at the rear of the tooth holder B serve as spacers for said holder members b.

Although the tooth C has only the single fastening bolt 34 therefor, it will be readily appreciated that the engagement of the dual bearings 29 on the tooth with the two seats 15 on the leading tip portions of the holder member b, coupled with the engagement of the tongue 27 of the tooth with the two stop lugs 18 on said portions of said members, results in a securely firm and durable connection between said tooth and the holder members, without any appreciable strain on said fastening bolt, and without any possibility of the tooth to pivot about said bolt.

Upon the removal of the tooth-attaching bolt 34 and the mere loosening of the remaining bolts clamping the holder members b together, the tooth C may be readily removed from said members and another tooth put in its place, it being necessary only to replace the tooth-attaching bolt 34 and re-tighten the remaining bolts to secure the substituted tooth firmly attached to said holder members.

The ready attachment of the tooth C to the companion holder members b and the corresponding readiness with which the tooth may be detached from such members, renders it easy for a used to substitute a new tooth for one worn beyond further usefulness, and also renders it easy for the user to interchange the teeth of scarifier elements, when desired, as for the purpose of obtaining uniformity of wear of such teeth.

The paired holder members b of a scarifier element are each reversible end-for-end, such reversibility of said members being desired in the event of the wearing off of the seat 15 of either member to an extent impairing the security of attachment of a tooth thereto. The double-tipped construction of said holder members, which renders possible the reversibility thereof, provides for doubling the life of said members, within favorable dimensional and weight limitations, as will be readily comprehended.

In either end-for-end relationship of either of the paired holder members b, the boss 20 will be socketed in the leading end of the slot 13 in the hanger bar A, and the boss 19 will be socketed in the one or the other of the openings 11, 12 occupying the leading position in the hanger bar. Correspondingly, the one or the other of the bosses 21, 22 will be socketed in the one or the other of said openings 11, 12 in the hanger bar occupying the trailing position.

The relative positioning of the openings 11, 12 and slot 13 in the hanger bar A renders it immaterial as to which one of the edges of said hanger bar is placed in leading position and this fact coupled with the further fact that either end of either of the two identical holder members b of a pair may take the leading position, greatly simplifies the requirements in manufacture and in assembly, as well.

The construction of the tooth C, though necessarily of hard, wear-resisting material, is relatively inexpensive, the entire element considered, since the major portion of the tooth structure may be worn away before the tooth becomes useless.

The paired holder members identically constructed of comparatively soft and relatively inexpensive material, are effectively guarded against wear at their leading tip portions by the

tooth clamped thereto, but when the seat 15 at such portion of either holder member becomes too far worn, upon the wearing away of the tooth, to afford a satisfactory tooth mounting, 5 the member will be reversed to present the previously trailing seat 15, if not already worn, in leading position, and thus provide an unimpaired support for one of the bearings 29 of a tooth. When both seats 15 of a holder member b have 10 been rendered useless by wear, said member will, of course, be discarded and a new one substituted therefor. Upon reversing either of the holder members b endwise to bring its previously trailing seat 15 into leading position for the application of a tooth thereto, such member will, of course, be shifted to the opposite side of the hanger bar A.

Among the numerous advantages residing in my present invention are included simplicity and 20 economy of manufacture and the ease of assembly, disassembly and rearrangement of parts, which permits the replacing and interchanging of such parts and also the reversal of the companion holder members to provide unworn tooth-supporting seats for those which have been impaired through wear. The provision by which the tooth structure may be practically entirely worn away before being rendered useless is an important feature of the invention. In addition 25 to performing its scarifying function, the tooth guards the companion plates of the composite tooth holder at the leading tip portions thereof where the greatest wear is encountered. The edgewise reversibility of the hanger bar A and 30 the endwise reversibility of the holder members b simplifies initial assembly of such parts of the scarifier element and likewise simplifies the subsequent rearrangement of said holder members in the assembly to renew either or both of the 35 tooth-supporting seats. The meshing or interlocking engagement of the tooth C with both of the holder members b affords an extremely rigid support for said tooth and, simplifying the connection between the tooth and hanger minimizes 40 the effort required in attaching the tooth to and detaching the same from said holder.

Changes in the specific form of my invention, as herein disclosed, may be made within the scope of what is claimed without departing from 45 the spirit of my invention.

Having described my invention, what I claim as new and desire to protect by Letters Patent is:

1. A scarifier element comprising a hanger bar, 50 an elongated tooth holder for attachment to said hanger bar, and a tooth for attachment to said holder, said hanger bar having a plurality of openings in the lower end thereof, extending therethrough and providing sockets at its opposite sides, said holder consisting of two plate-like members of identical formation, the edge of each member providing a seat at each tip portion of such member, said holder members being adapted to be assembled on the hanger bar in registry, one with the other, with their inner faces facing 55 each other and with the tip portions thereof at one end of the assembly in a leading position, each holder member having a plurality of bosses at its medial portion issuing from its inner face, a number of such bosses being adapted to fit in 60 the sockets in either side of the hanger bar, each holder member having bores therein including a bore in each tip portion thereof and bores extending through said bosses, said tooth having an attaching tongue issuing therefrom at the 65 rear thereof and receivable between the inner 70 75

faces of the leading tip portions of the assembled holder members, bolts received in said bores in said holder members for securing said members to each other and to the hanger bar, said attaching tongue having a bore therein to receive the bolt in the leading tip portions of the holder members, said tooth having dual bearings, one at each side of said tongue, each bearing being adapted to bear against the seat at the leading tip portion of its corresponding holder member, said tooth being detachable from and reattachable to the holder members without the detachment of either of said members from the hanger bar, and said holder members being detachable from the hanger bar and reattachable thereto in relation endwise reversed and transposed relative to the hanger bar for application of the tooth to the previously trailing tip portions of said members.

2. A scarifier element comprising a hanger bar, an elongated tooth holder for attachment to said hanger bar, and a tooth for attachment to said holder, said holder consisting of two plate-like members of identical formation, means for medially attaching said holder members, in assembled relation, to said hanger bar at opposite sides of said bar to bring said members into registry, one with the other, with their tip portions at one end of the holder in a leading position, each holder member having a bore therein at each tip portion thereof, said tooth having an attaching tongue issuing therefrom and receivable between the adjacent faces of the leading tip portions of the assembled holder members, bolts received in said bores in said holder members, said tongue having a bore therein receiving the bolt in the leading tip portions of the holder members, each holder member having a lug at each tip portion thereof, such lugs at the leading tip portions of said members being engaged by the tongue of the tooth and serving to prevent the tooth from pivoting in one direction about the bolt therein, such lugs at the trailing portions of said holder members serving to space the same apart, said holder members being detachable from the hanger bar and reattachable thereto in endwise reversed relation for application of the tooth to the previously trailing tip portions of said members.

3. A scarifier element comprising an upright hanger bar, an elongated tooth holder and a tooth, said holder consisting of two plate-like

members of identical formation, each member having a continuous marginal flange at its outer face lending increased thickness to the member about the edge thereof, said holder members being medially bolted to the hanger bar at opposite sides thereof and in registry, one with the other, with their inner faces spaced apart in facing relationship and with the tip portions thereof extending fore and aft of said hanger bar, the leading tip portions occupying a depressed position, the flanged edge of each member providing a seat at each tip portion of such member, each holder member having a bore in each tip portion thereof, said tooth having an attaching tongue issuing therefrom at the rear thereof and receivable between the inner faces of the leading tip portions of the assembled holder members, bolts received in said bores in said holder members, said attaching tongue having a bore therein to receive the bolt in the leading tip portions of the holder members, said tooth having dual thrust bearings, one at each side of said tongue, each bearing seating against the seat at the leading tip portion of its corresponding holder member, said tooth closing the space between said holder members and shielding said members at their leading tip portions, said holder members being detachable from the hanger bar and reattachable thereto in relation endwise reversed and transposed relative to the hanger bar for application of the tooth to the previously trailing tip portions of said members.

4. A scarifier element comprising an upright hanger bar, an elongated tooth holder, and a tooth, said holder consisting of two similarly formed plate-like members, each member having a tip portion, the edge thereof providing a seat, said holder members being bolted to the hanger bar at the opposite sides thereof and in registry, one with the other, with their inner faces spaced apart in facing relationship and with the tip portions thereof extending forwardly of the hanger bar in a leading position, said tooth having dual bearings, each thereof being adapted to bear against the seat at the tip portion of one of the holder members, and means for retaining the tooth in seated position on the tip portions of the assembled holder members, said tooth closing the space between the spaced holder members and shielding said members at their tip portions.

IRA SUBLETT.
